(57) **CLAIM**

The ornamental design for a display screen or portion thereof with a transitional graphical user interface, as shown and described.

DESCRIPTION

The patent or application file contains at least one drawing executed in color. Copies of this patent or patent application publication with color drawings will be provided by the Office upon request and payment of the necessary fee.

FIG. 1 is a front view of a display screen or portion thereof with a transitional graphical user interface showing a first image of the claimed design;

FIG. 2 is a second image thereof;

FIG. 3 is a third image thereof;

FIG. 4 is a fourth image thereof;

FIG. 5 is a partially enlarged view of FIG. 1;

FIG. 6 is a partially enlarged view of FIG. 1;

FIG. 7 is a partially enlarged view of FIG. 1;

FIG. 8 is a partially enlarged view of FIG. 3;

FIG. 9 is a partially enlarged view of FIG. 3; and,

FIG. 10 is a partially enlarged view of FIG. 3.

The appearance of the transitional image sequentially transitions between the images shown in FIGS. 1 to 4.

The subject matter in this patent includes a process or period in which an image changes into another image. This process or period forms no part of the claimed design.

The dashed broken lines illustrate the display screen or portion thereof and form no part of the claimed design.

The dot-dash broken line at the periphery of each of FIGS. 5-7 illustrates an extent to which that figure is enlarged from FIG. 1, and forms no part of the claimed design.

The dot-dash broken line at the periphery of each of FIGS. 8-10 illustrates an extent to which that figure is enlarged from FIG. 3, and forms no part of the claimed design.
